Louis Meylach
By Wilbur M. Stone
their Attorney.

UNITED STATES PATENT OFFICE.

LESLIE M. PAGE, OF MAPLEWOOD, NEW JERSEY, AND LOUIS MEYLACH, OF BROOKLYN, NEW YORK.

PRESSING BLOCK.

Application filed April 2, 1925. Serial No. 20,223.

To all whom it may concern:

Be it known that we, LESLIE M. PAGE and LOUIS MEYLACH, citizens of the United States, and residing, respectively, at Maplewood, in the county of Essex and State of New Jersey, and at New York, borough of Brooklyn, in the county of Kings and State of New York, have invented certain new and useful Improvements in Pressing Blocks, of which the following is a specification.

This invention relates to pressing blocks and particularly to such blocks as are employed in the pressing of hats and hat linings.

The object of our improvements is to provide a pressing block of simple construction having improved means for heating and steaming the articles applied thereto.

With these ends in view and others which will appear later herein, our improvements include, in their preferred embodiment, features illustrated in the accompanying drawing, wherein:

Figure 1 is a cross sectional elevation taken on line 1—1 of Fig. 2. Fig. 2 is a similar section taken on line 2—2 of Fig. 1. Fig. 3 is a diagrammatic plan view of the heating coil. The scale of all the figures is the same and is about half the size of the actual device.

The present invention is in the nature of an improvement of a portion of the hat lining blocking machine shown in our pending application Ser. No. 737,248, filed September 12, 1924, and is directed to higher efficiency and better control of the heating and steaming features of that application.

In the present case hollow body 4 of dome-shaped contour and somewhat longer one way than the other to conform approximately to the shape of the human head, may be supported by a frame having a floor 5 from which project downwardly one or more legs 3 to some suitable support, not shown. Block body 4 is preferably of metal and may be removably attached to frame floor 5 by screws as 6, and said floor is provided with opening 20 therethrough for the passage of steam from some known source of supply, not shown.

In the upper part of block 4 is chamber 7 opening upwardly for the reception of electric heating coil 8, of known construc-

tion, and which coil is shown in plan view in Fig. 3, the opposite ends 9, 9^a of the wire thereof leading off to the right. Said block 4 is provided with cap 10 for chamber 7 and which cap may be secured in place by screws as 11 passing upwardly through lower wall 12 of said chamber and threaded into said cap. Said coil may be held in place in chamber 7 by packing discs 13, 13. Leading to the right from chamber 7, Fig. 1, and then downwardly to the base of block 4 is channel 14 within the foot of the metal of said block. Through this channel the ends 9, 9^a of the wire of coil 8 are led to some known source of electric energy, not shown. For securing those portions of wire 9, 9^a where they extend outwardly from the base of block 4, clamp members 16, 17 are provided, suitably chambered for said wire. Said clamp members are secured together and to the base of block 4 by suitable screws as 18.

Cavity 15 within block 4 serves as a steam chamber and vents 19 are provided for the passage of the steam outwardly against an article applied to the outside of said block. The locating of the electric heating device in the dome of block 4 serves a double purpose, first, for heating an applied hat lining at the desired portion thereof and second, for superheating the steam admitted to cavity 15 through opening 20, whereby the steam is ejected in dry condition through vents 19. Also, chamber 7 and channel 14 leading therefrom to without the base of block 4 are entirely isolated from steam cavity 15, thereby preserving the coil and leading wires from any ill effects of direct contact with steam or other deleterious influences.

The present improvements enable an operator to produce more work of better character and with less effort than heretofore known. Also, the segregation of the electric features of the device is conducive to long life and efficient operation of the coil and its connections.

We claim:

1. A pressing block including in combination a block body of hollow dome-shaped construction, a floor for closing the lower portion thereof whereby a cavity is enclosed within said body, a chamber in the upper domed portion of said body opening upwardly and isolated from said body

cavity, an electric heating coil within said chamber, wires attached to said coil, a cap for closing the upper opening to said chamber, and a channel within the side wall of said body leading from said coil chamber to the foot of said body for the passage of the coil connecting wires.

2. A pressing block including in combination a block body of hollow dome-shaped construction, a floor for closing the lower portion thereof whereby a cavity is enclosed within said body, a passage for steam into said cavity, a coil chamber in the upper domed portion of said body opening upwardly and isolated from said body cavity,

steam vents through said block body adjacent said coil chamber, an electric heating coil within said chamber, wires attached to said coil, a cap for closing the upper opening to said chamber, and a channel within the wall of said body leading from said coil chamber to the foot of said body for the passage of the coil connecting wires, said channel being isolated from said body cavity.

In witness whereof, we hereby affix our signatures this 30th day of March, 1925.

LESLIE M. PAGE.
LOUIS MEYLACH.
